UNITED STATES PATENT OFFICE

ADOLPH K. MALMQUIST, OF SOUTH BELLINGHAM, WASHINGTON

CAN SEALING MACHINE

Application filed October 3, 1928. Serial No. 309,978.

This invention relates to can-closing apparatus and has special reference to machines of that type in which the can tops are seamed onto the can bodies in a vacuum chamber, the present invention providing a rotating carrier by which a plurality of cans will be carried through the sealing chamber at one time and the tops applied by a double seaming operation. The general object of the invention is to simplify the construction, accelerate the operation, and reduce the cost of maintenance of can-seaming machines.

More specifically stated, the objects of the invention are to so mount the vacuum chamber that it may revolve easily while being supported firmly and well balanced; to provide a sectional casing for the sealing vacuum chamber which may be easily adjusted to compensate for wear while minimizing frictional wear caused by atmospheric pressure when the chamber is vacuumized; to provide a vacuumizing groove or port of such design that spillings from the cans will be drawn out of the chamber with the air and thereby prevented from collecting in the bottom of the chamber and working into the plunger bearing; to separate the spillings from the air drawn from the vacuum chamber and thereby avoid clogging of the vacuum pump; to provide an arrangement of ports whereby the seaming rollers may be lubricated and adjusted from the exterior of the casing so that no disassembling is necessary; to provide novel and efficient top-feeding means controlled by the supply of cans so that a top will be fed to the seaming chamber only when a can is in position to receive the top; to provide means for automatically marking the can tops; to minimize spilling by placing the cans each having a loose top thereon in the seaming chamber close under the seamer chuck and between the seaming rollers and vacuumizing the cans before clinching the caps, to prevent rotation of the cans and caps, to align the cans in single file as they are fed to the machine, and to provide a mechanism by the use of which the cans will at all stages be caused to travel smoothly and without spilling under normal conditions. The stated ob-

jects and other objects which will appear incidentally in the course of the following description are attained in such an apparatus as is illustrated in the accompanying drawings, and the invention resides in certain novel features which will be particularly pointed out in the appended claims.

In the drawings:—

Figure 1 is a top plan view of an apparatus embodying the invention.

Figure 2 is a similar view with the top spiders or cap plates removed and some parts in horizontal section,

Figure 3 is a vertical section about on the line 3—3 of Fig. 1,

Figure 4 is an enlarged vertical section through the can and cap clamping plungers of the vacuum chamber,

Figure 5 is a view partly in vertical section and partly in side elevation, looking at the power side of the apparatus, this view being somewhat diagrammatic,

Figure 6 is a detail plan view of a part of the cap-feeding apparatus,

Figure 7 is a longitudinal section through the parts shown in Fig. 6,

Figure 8 is a detail transverse section approximately on the line 8—8 of Fig. 7,

Figure 9 is a schematic plan view of the support for the cap-feeding apparatus,

Figure 10 is a detail of the bottom of the cap magazine,

Figure 11 is an enlarged detail section on the line 11—11 of Fig. 9,

Figure 12 is a schematic plan view of the gearing,

Figures 13, 14 and 15 show the plunger of the transfer turret in elevation, vertical section and top plan, respectively,

Figure 16 is an enlarged plan view and Figure 17 an edge view of the cam for actuating the marker,

Figure 18 is a horizontal section through the sealing or vacuum chamber and the carrier therein, the seaming rollers and mechanism being omitted,

Figure 19 is a schematic vertical section of the same,

Figure 20 is a plan view of the valve or

can carrier, the seaming devices being omitted,

Figure 21 is a diametrical vertical section of the same,

5 Figure 22 is a partial elevation of the same,

Figure 23 shows in detail the sill provided at the entrance to the vacuum chamber,

Figure 24 is a top plan view of a part of the valve or can carrier,

10 Figure 25 is a vertical section on the line 25-25 of Fig. 24,

Figure 26 is a horizontal section through one compartment of the can carrier,

15 Figure 27 is a vertical section on the line 27-27 of Fig. 26,

Figure 28 is a schematic view showing the seaming rollers in a position different from that shown in Fig. 26,

20 Figure 29 is an elevation of the seaming rollers and the cam for shifting them,

Figures 30 and 31 are detail elevations of the levers or arms which carry the seaming rollers,

25 Figure 32 is a detail section of the spindle shown in Fig. 25,

Figure 33 is a detail plan view of a dial shown in Fig. 24,

30 Figure 34 is an enlarged plan view of the cam which controls the seaming roller, arms or levers,

Figures 35 to 40 are details of the can supporting plunger in the carrier,

35 Figures 41 and 42 are details of the chuck or cap-pressing members,

Figure 43 and 44 are details of the can-discharging elements.

40 The main frame includes a base plate 1 of suitable form supported by legs 2 which may be of any approved design and may be integral with or rigidly secured to the plate.

There is also a spider 3 carried by columns or posts 4 rising from the base plate, and a rim or flange 5 on the base supports the casting 6 of the vacuum and sealing chamber.

45 Rigidly secured upon the base plate and projecting laterally therefrom is a feed table or bracket 7 at the outer end of which is suitably mounted a shaft 8 carrying a drum or roller 9 about which is trained the delivery

50 bight of an endless belt conveyer 10 which brings the filled cans to the seaming machine. Sprocket gearing 11 operatively connects the shaft 8 with a shaft 12 mounted at the inner end of the feed table and driven through a

55 train of gearing from the main power shaft 13 which is mounted below the base plate 1 and is equipped at one end with a band pulley 14 whereby it may receive power from any convenient motor.

60 Parallel longitudinal slots 15 in the feed table accommodate carrier chains or belts 16 which are trained about vertically disposed pulleys or sprockets 17, 18 and which receive the cans and co-operate with other elements to transfer them

65 in proper timed relation to the cap and body

assembling turret, the sprockets or pulleys 18 being secured upon the shaft 12. The carriers 16 operate between a stationary guide rail 19 and a movable guide rail 20 so that if

10 the cans received from the conveyer 10 are out of exact alinement they will be properly alined before leaving the feed table. The

movable rail is pivoted at its inner end, as at 21, and its free end may be moved laterally

15 outward by impact of an on-coming can and is yieldably pressed inwardly and held parallel with the rail 19 by a spring 22 secured upon the feed table and bearing against the outer side of the rail.

The outward movement of the rail is limited by a stop 23, and, consequently, any can which may be out of

20 line will be properly centered upon the carriers 16 as it travels along between the guides.

Disposed in a horizontal plane above the feed table and arranged to form an acute angle

25 with the carriers 16 is an endless feed chain 24, some of the links of which are equipped with pusher fingers 25 adapted to project over the rail 19 successively and at regular

intervals to engage behind the cans on the carriers 16 and push them around to and into

30 the can and cap assembling turret in properly timed relation. The chain 24 is carried and actuated by sprockets 26, the outer sprocket

35 being mounted in an adjustable bearing bracket 27 whereby it may be kept taut, and the inner sprocket being secured upon a vertical shaft 28 which is mounted in and ex-

30 tends below the feed table. Beveled gearing

35 29 operatively connects the shaft 28 with the shaft 12 and a spur gear 30 on the lower end

40 of the shaft 28 is a member of the gearing train which transmits motion from the main driving shaft 13. An arcuate guide rail 31

45 concentric with the shaft 28 and the pulley thereon, and a straight guide rail 32 tangential to said pulley direct the cans into the

40 can and cap assembling turret.

50 Secured in any convenient manner upon one side of the main frame is a bracket 33 and an upper spider 34 in which is journaled a vertical shaft 35 carrying the can and cap assembling turret 36, the cap magazine and the cap-feeding mechanism being also mounted on said bracket.

55 The turret comprises a central hub or circular body from which equidistant approximately tangential pushers 37 project, said pushers being formed with

60 horizontal notches 38 to clear stop lugs on the wall of the sealing and vacuum chamber,

65 and having an outline which defines a semi-circular seat or pocket 39 to receive a can.

The parts are so timed that a can seat or

70 pocket will be disposed adjacent the guide 32 as a can is pushed along said guide by a pusher finger 25 so that the can will be received in the pocket and will rest on the bottom plate

75 40 of the turret. The rotation of the turret will carry the can past the cap magazine to

70 receive a cap and, just before a complete revo-

115

120

125

130

lution is made, will bring the can against a cam stop lug and guide 41 on the vacuum sealing chamber casing, at the entrance thereto, whereby the can will be directed into said chamber. In passing to the sealing chamber, the can travels between the parallel opposed faces of the stop lug 41, secured on the wall of the sealing chamber, and a cooperating lug 42, fixed on the base, which latter lug 10 also functions to guide a sealed can discharged from the sealing chamber onto the delivery table 43, as will presently appear.

At a point remote from the entrance to the sealing chamber and, for convenience, diametrically opposite the entrance, the can receives a cap. The cap magazine consists of four rods 44 rising from the bracket 33 in rectangular relation and the caps are stacked between the rods in an obvious manner. A 20 straight slot 45 is formed through an extension of the bracket 33 longitudinally of the extension and in radial relation to the cap magazine and a dovetailed groove 46 is formed in the upper side of the extension with 25 its sides parallel with the sides of said slot. A dovetailed cap-pusher slide 47 is seated in the groove 46 and is provided with a longitudinal slot 48 registering with the slot 45, the working end of the slide having a recess 30 49 and an overhanging beveled lip 50 whereby it is adapted to engage the lowermost cap 51 and push it from the stack to the marker station. The stack of caps will be supported by the slide until the slide is retracted where- 35 upon the entire stack will be lowered to dispose the lowermost cap in position to be engaged by the pusher slide. Slidably supported by the gibs 52 and 53 on the bottom of the bracket extension is a head 54 which 40 extends upwardly through the slots 45 and 48 and is provided with a notch 55 in its upper end, this head being reciprocated continuously when the machine is in operation. Pivoted upon the upper side of the pusher 45 slide 47, near the outer end thereof, is a dog 56 which at times engages the notch 55 to thereby lock the slide to the head and effect operation of the slide and feeding of a cap. Normally, the dog is held out of engagement 50 with the head by a spring 57 anchored on the pivot for the dog and bearing against the inner side of a lug 58 on the dog near the free end thereof. When the dog is engaged with the head, it is held in such engagement 55 by a stationary guide bracket 59 against which it rides during a full operation of the slide, as will be understood from the drawings. The dog is rocked into engagement with the driving head of a two-armed lever 60 fulcrumed upon the extension of the bracket 33 with its outer end bearing against the outer side of the dog and its inner end disposed normally in the path of the can which is beginning to travel with the turret, being 65 yieldably held in such position by a spring

61 which is anchored at one end upon the fulcrum and has its free end engaged with a lug 62 on the lever. It will be noted that the arms of the lever define an obtuse angle and the inner end of the lever projects into 70 the path of a can carried by the turret adjacent the end of the guide 32 so that, as a can clears said guide and starts to travel with the turret, the lever will be rocked and will drive the dog 56 into engagement with the head 54. It will thus be seen that the caps will be fed from the magazine in consonance with the travel of the cans.

As above stated, the cap is pushed from the magazine to a marker station. The marker may be of any approved detail construction and is shown as comprising hinged-connected die-carrying jaws 63 normally separated by a spring 64 to receive a can top or cap. From the marker, the cap passes into 80 a pocket of the turret where it is received and held by a plunger head 65 on the lower end of a plunger rod 66 which is slideable vertically in the top of the turret, it being noted that a plunger is provided for each 85 pocket of the turret. The plunger head is open at its outer side 67 to readily admit the cap and is also laterally extended, as at 68, to compensate for the relative angular movement between the turret and the cap and avoid damage to the cap as it enters the plunger head. The cap engages at its edge in an internal groove 69 in the head whereby it is supported above the can until lowered 90 onto the same just as it is to be transferred to the sealing chamber. To prevent turning of the plunger in the turret, the plunger rod is equipped with a key or feather 70 fitting in a groove provided therefor in the top plate of the turret, and at the upper end 100 of the rod is mounted a roller 71 traveling in a cam track 72 on the spider 34 whereby the cap will be lowered onto the can at the proper instant.

On the under side of the head 54 is a depending stud 73 upon which is pivotally engaged one end of a pitman 74, the opposite end of the pitman being pivotally connected to a crank arm 75 on the upper end of a shaft 76 which is journaled in suitable bearings 110 on the bracket 33 and the main frame. To the lower end of the shaft 76 is secured a crank 77 to which a link 78 is attached, said link being in turn pivoted upon a wrist pin 79 which is carried by a shaft 80 journaled in the lower portion of the bracket 33. On said shaft 80 is a pinion 81 meshing with a large gear 82 on the lower end of the turret-carrying shaft 35. On the upper end of the shaft 80 is a crank 83 to which is pivoted one end 115 of a link 84 having its outer end pivoted to a lever 85 secured to the lower end of a vertically disposed rock shaft 86 which is journaled in the bracket 33. On the upper end of the shaft 86 is secured a bent lever 87 to the 120

130

outer end of which is secured an arcuate push bar 88 slidably fitted in a groove 89 in the top of the bracket 33 to pass the marker dies and transfer the marked cap to the plunger head 65, and it should be noted at this point that the rods 44, constituting the cap magazine, are carried by a base plate 90 which is spaced from the top to the bracket a distance equal to the thickness of a cap and its bead or flange, guide plates 91 being secured on the bracket to direct the cap properly to the marker. It will be readily seen that the pusher bar 88 will be reciprocated in timed relation to the other working parts so that it transfers a marked cap and is then retracted to permit the placing of another cap in the marker. On the edge presented to the pusher, the plate is recessed or undercut, as at 290, to accommodate the lip 50 and permit the pusher to make a full stroke.

Spanning the marker is a post 92 which forms a stop for the cap delivered to the marker, and on which is a barrel 93 in overhanging relation to the marker. Slidably fitted through the barrel 93 and resting on the upper member of the marker is a striker rod 94 which is normally held raised by an expansion spring 95 disposed between the upper end of the barrel and a head or abutment 96 on the rod, the upward movement of the rod being limited by a stop collar 97 secured on the rod below the barrel. To regulate the opening or separation of the marker dies, a hand screw 98 bears on the upper end 35 of the striker rod, said screw being equipped with a hand wheel 99 and threaded through the split end of a lever 100 carrying a set screw 101 to maintain the adjustment. The lever 100 is fulcrumed between its ends on the spider 34 and its inner end rests on a cam 102 which is secured on the shaft 35 above the spider 34, an anti-friction bearing 103 being provided on the spider, if desired to reduce the wear. The cam, of course, rotates with the turret and the shaft 35 and at proper intervals a high part 104 will ride under the lever 100 and rock the same to deliver a quick sharp blow upon the rod 94 and mark the cap.

The sealing and vacuum chamber is arranged in the angle defined by the can-feeding mechanism and the can and cap-assembling and transfer turret. The wall 6 of said chamber is in three arcuate sections 105, 106 and 107 each of which has a horizontal flange 108 at its lower edge resting on the base 1 or the rim thereon and provided near its ends with slots 109 through which cap bolts 110 are inserted into the base to secure the wall on the latter and permit adjustment of the wall to effect the desired air-tight engagement with the valve or can carrier and compensate for wear without interfering with the rotation of the carrier. The ends of the several sections are beveled or disposed obliquely whereby they may abut, as shown at

111, with their inner peripheral surfaces flush, and the ends of the central section 105 are formed with horizontal slots 112 through which cap bolts 113 are inserted into threaded sockets provided therefor in the adjacent ends 70 of the sections 106 and 107, the sections being thus firmly secured together while the slots 112 permit relative adjustment of the sections 106 and 107 upon the ends of section 105. It will be noted that the ends of the sections 106 and 107 are cut away in angular form, as shown at 114, and within said recesses eye bolts or brackets 115 rise from the base. Swiveled in the upper ends of the brackets 115 are adjusting screws 116 which have 80 their threaded ends engaged in threaded sockets 117 in the respective sections 106 and 107. Obviously, manipulation of the adjusting screws will set the wall sections in proper relation to the carrier and they will be firmly secured in the set positions by turning the set bolts 110 home.

In the inner surface of each wall section, at the lower limit of the effective area thereof, is a circumferentially extending groove 118, said groove extending through the full length of the center section but terminating short of the outer ends of the end sections and constituting a continuous passage or port extending from a point near one end of the wall to a point correspondingly near the opposite end of the wall. In the section 107, the groove communicates directly with a port 119 leading outwardly through the flange 108 and having a nipple 120 secured in its outer end. A hose or pipe 121 is attached to the nipple 120 and leads downwardly therefrom to discharge into a vacuum tank 122 through the side of the latter, the upper end of the tank being operatively connected in any approved manner to a suction pump (not shown) which may be of any preferred design. It will be understood that by having the groove 118 and the port 119 at the bottom of the vacuum chamber, any liquids or acids which may spill from the cans will be drained from the chamber with the outflowing air and will collect in the vacuum tank, instead of remaining in the chamber to eat away the plunger or other working parts. The tank is provided at its bottom with a drain cock 123 in order that the accumulated liquor and sediment may be drawn off from time to time.

Extending centrally through the vacuum and sealing chamber is a vertical shaft 124 which is journaled in the base 1 and the spider 3 and to which the valve or can carrier is secured, said carrier comprising a hub 125 keyed to the shaft 124 and a circular body so formed as to define a plurality of pockets 126 containing seaming mechanism. The circular body also furnishes a floor or bottom plate 127 extending to the wall 6, and an annular wall 128 through which openings 129 are formed to permit the entrance of the cans into 130

and their discharge from the respective pockets. At each of said openings a guide plate or sill 130 is provided to fill the space between the turret and the seaming plunger, 5 to be presently described, a smooth passage of the can onto the plunger being thereby insured. A head frame 131 is secured in any convenient manner to the carrier and constitutes a top or cover for the several pockets, 10 being provided with portions 132 fitting within the respective pockets and also with upstanding bearing sleeves 133 over the same.

On the under side of the carrier, concentric 15 with each pocket, is a guide bracket 134 which is rigidly secured to the carrier and is of a generally cylindrical formation to slidably house a tubular plunger 135, a packing gland 136 being provided in the upper end of the 20 guide around the plunger to prevent leakage. The lower end of the plunger is closed, as shown at 137, and in the upper end of the plunger is secured a bushing 138 snugly receiving the stem 139 depending from the 25 plunger head 140 onto which the can, with a top or cap loose thereon, slides when it enters the pocket of the carrier. A stop collar 141 is secured on the lower end of the stem 139 and is adapted to abut the bushing 138 30 with sufficient force to frictionally hold the stem against turning about its own vertical axis. To maintain the frictional engagement of the collar and the bushing, an expansion spring 142 is seated on the lower closed end 35 or head 137 of the plunger and bears at its upper end against an abutment 143 below the stem, a bearing ball 144 being interposed between the abutment and the end of the stem, as shown. The spring normally maintains 40 the parts 138 and 141 in engagement so that they constitute a brake to prevent rotation of the can until after it is vacuumized. In the lower end of the plunger 135 is secured diametrically an axle 145 having rollers 146 45 and 147 mounted thereon, the roller 146 being disposed concentrically and the roller 147 being disposed eccentrically or at the outer side of the plunger. These rollers cooperate respectively with cam tracks 148 and 149 50 which are secured upon the base plate concentric with the carrier shaft 124, the action of the cam 148 being to lift the plunger and the cam 149 having a reentrant or overhanging flange which acts to depress the plunger, as 55 will be understood. When the plunger is raised, the bushing will be lifted from the collar 141 and the stem, plunger head, and can thereon may then rotate upon the ball 144 about the axis of the plunger head and the 60 stem.

In the top of each pocket 126, aligned axially with the seaming plunger therein, is a chuck 150 rotatably mounted in and extending through the bearing sleeve 133. The head 65 151 of the chuck has secured to its under side

a ring 152 having the marginal portion of its lower face properly shaped, as at 153, to fit over the inner bead of the can cap and within the marginal bead or flange thereof. Interposed between the head 151 and the top of the frame 133 is an antifriction thrust bearing 154, a rim 155 on the head enclosing the bearing and forming a well for lubricant, and it may be here noted that, wherever the structure will permit, bearings will be of the anti-friction type and rotating parts will be formed with passages for receiving and retaining lubricant. In the upper end of the stem of the chuck is a recess 156 receiving an expansion spring 157 bearing upon the bottom of the recess and an abutment or plug 158 which is secured upon the upper end of a presser rod 159 and has lateral arms 160 in constant engagement with a stop and guide plate 161 whereby the rod 159 is prevented from turning but may slide vertically, the spring 157 moving the rod upwardly and a cam rail 162 on the spider 3 moving it downwardly in an obvious manner. On the lower end of the rod 159 is a cap-holding disk or 80* head 163 which projects slightly below the chuck head 151 when in active position and seats in a central recess 164 therein when in inactive position. While the presser rod does not rotate, the chuck rotates constantly 85 and, to effect such rotation, a pinion 165 is secured on the stem of the chuck and meshes with a gear 166 which rests on the upper end of the carrier hub and rotates about a bushing 167 which encircles the carrier shaft 124. 90 A bevel gear 168 secured on the upper side of the gear 166 meshes with a similar gear 169 on the inner end of a shaft 170 mounted radially on the spider 3. Beveled gearing 171 connects the outer end of the shaft 170 with the upper end of a vertical shaft 172 on the main frame, and on the lower end of the shaft 172 is a beveled gear 173 meshing with gear 174 on the inner end of the power shaft 13. This driving mechanism and the described stationary cams are so timed that, just prior to the discharge of the can and cap from the transfer turret, the cap will be placed in position on the can and will rest loose thereon. The assembled cap and can are received on the seaming plunger with the cap below and out of contact with the constantly rotating chuck, and, as the can reaches its proper seat on the plunger, the presser rod descends onto the cap and holds it 100 close on the can. The can and cap are thus held until after they enter the vacuum field and reach the point where the seaming operation begins, the presser rod then yielding somewhat to the suction so that all air may be 105 withdrawn from the can without causing complete separation of the cap and can. It will be understood that the rod exerts just enough pressure on the cap to keep it from sliding off the can while permitting the for- 110 115 120 125 130

mation of an air space sufficient to permit escape of all the air in the can. This loose assembling of the caps and cans is an important feature of the present invention. When the cans are vacuumized, fruit therein tends to swell and rise as the suction opens the pores or cells in the food but the liquid is not so affected, in fact, the level of the liquid will drop a little as the fruit rises. When the cap is loose, as in the operation of the present machine, the swelling fruit and the suction will lift the cap above the liquid line and make an air space, permitting all the air to be exhausted without drawing the syrup out with the air. If the cap be clenched before vacuumizing, as was the previous general practice, the fruit can not rise, but as it swells, will press against the cap and cause the liquid level to rise until it is close to, if not in actual contact with, the cap so that the suction will draw the liquid out with the air. This action creates a costly waste of syrup and also increases the cost of upkeep as the syrup runs over the working parts of the machine and gums the same so that it is almost impossible to keep the machine operating continuously. This described waste of syrup is so minimized in my present machine as to be practically eliminated and the machine may be operated over a long period without interruption. When the can and cap arrive at the point where seaming begins, the described vertical movement of the seaming plunger occurs and the presser rod simultaneously clears the cam rail 162 so that the can and cap are raised to the chuck and clamped by and between the chuck and the plunger with the edge of the cap in the working plane of the seaming rollers, whereupon the can and cap will spin with the chuck.

The seaming rollers 175 and 176 operate at the opposite sides of the chuck and are carried respectively by bent levers 177 and 178 which are mounted intermediate their ends upon eccentric pins or posts 179 extending through and depending from the top of the frame 131. Springs 180, secured on the levers and bearing against the side walls of the pockets, tend to hold the outer ends of the levers and the seaming rollers away from the chuck while cams 181 and 182, located between the inner ends of the levers, act thereon to swing the levers and the rollers toward the chuck and into pressing contact with the cap. The cams are oppositely disposed and are formed or secured on the upper end of a shaft 183 which is journaled in and extends vertically through an opening 283 provided thereof in the hub portion of the carrier or valve, and on the lower end of which is secured a pinion 184 meshing with an annular rack 185 at the upper end of a stationary bushing 186 which forms a part of lower bearing support for the carrier shaft 124. On the lower end of the shaft 124 is secured a

gear 187 meshing with a gear 188 on the vertical transmission shaft 172 whereby the desired rotation of the carrier or valve is effected.

It is to be noted that the seaming rollers are mounted for free rotation on their respective levers or carrying arms and are provided with peripheral grooves 189 of proper form to engage the beads or flanges of the cap and can and crease the same together so as to effectually seal the can. The cams 181 and 182, being oppositely disposed, will move the seaming rollers alternately to active position and they are so shaped that each roller will be active while the carrier is turning through an arc of about ninety degrees while the port or passage 118 in the wall of the sealing chamber extends through somewhat more than one-half of the annular length thereof, and the ends of said wall are spaced apart about ninety degrees between the points 190 and 191 to provide an opening through which the cans are received from the transfer turret and discharged onto the delivery table 43, the distance from the points 190 and 191 to the respective ends of the passage 118 being greater than the width of the opening 129 in the side of the carrier through which the cans are admitted and discharged. It, therefore, will be readily understood that before the advancing wall of the opening reaches the port or passage 118 the trailing wall of the pocket will pass the point 191 and the pocket will be closed to the outside air. The can is subjected to the vacuumizing action between the initial end of the air port and the point 192, at which point the can and cap are clamped between the spinning chuck and the seaming plunger in the manner previously described. The first seaming roller then immediately acts on the spinning cap and can and continues to act until the can has traveled through about ninety degrees to the point 193 whereupon the second roller becomes active and operates until the point 194 is reached, said point being beyond the end of the air passage and near the point of discharge onto the delivery table. At the point 194, the sealed can is lowered from the chuck and the discharge lever or pusher 195 comes into play. This lever is disposed below the seaming roller 175 and is secured upon the upper end of a rock shaft 196 which extends through an opening 296 in the bottom of the carrier and is equipped at its lower end with a crank 197 adapted to impinge against a stationary cam 198 on the rim 5 of the base plate whereby as the seaming operation is completed the pusher will be rocked against the can and will slide the same out through the opening 129 onto the delivery table 43.

A gear 199 on the underside of the delivery table meshes with the gear 187 so that the table will be continuously driven. A gear 200 is secured concentrically to the gear 187

and intermediate gears 201, 202 and 203 transmit motion from the gear 200 to the gear 82, to drive the turret and the cap-feeding devices, and to the gear 30 to actuate the 5 can-feeding mechanism.

The eccentric fulcrum pin 179 has its upper end preferably square whereby it may be turned by a wrench and it is fixed in any convenient manner to a cap plate 204 which rests 10 on the frame 131 and is provided with a concentric slot 205 through which a stud 206 is inserted into the frame. By turning the pin, the lever may be set to hold the seaming roller closer to or farther from the center of 15 the chuck and the pressure upon the can thereby regulated. To insure accuracy in adjustment, telltale lines 207 may be provided on the frame and on the beveled edge of the cap plate. It will be noted that an oil passage 20 extends through the eccentric fulcrum pin, the lever and the pivot of the seaming roller so that the roller may be lubricated and adjusted from the outside of the valve or can carrier.

25 Having fully described my invention what I claim as new and desire to secure by Letters Patent, is:—

1. In an apparatus for the purpose set forth, the combination of a stationary casing, 30 a continuously rotating can carrier therein, said casing and carrier forming a vacuum chamber, means for continuously supplying loosely assembled cans and caps to the can carrier, and means within the can carrier for 35 seaming the caps onto the cans, the top and bottom of the can carrier constituting the top and bottom of the vacuum chamber.

2. In apparatus for sealing cans in vacuum, 40 the combination of a vacuum chamber having an opening in its side and having a port communicating through its side with a source of suction, a continuously rotating can carrier having an opening in one side to receive and discharge cans through the opening in the 45 side of the vacuum chamber, the can carrier closing the sealing chamber to the atmosphere, seaming mechanism carried within the can carrier, and means mounted in the top and bottom of the can carrier to present a 50 can and loosely assembled cap to the seaming mechanism and maintain them in operative relation thereto.

3. In apparatus for sealing cans in vacuum, 55 the combination of a vacuum chamber having an opening in its side and having a port communicating through its side with a source of suction, a continuously rotating can carrier having an opening in one side to receive and discharge cans through the open side of the 60 vacuum chamber, the can carrier closing the sealing chamber to the atmosphere, seaming mechanism carried in the top of the can carrier, means mounted in the top and bottom of the can carrier to present a can and loosely 65 assembled cap to the seaming mechanism and

maintain them in operative relation thereto, means carried by the can carrier for discharging the can, and means external to the can carrier for actuating the discharging means.

4. In an apparatus for seaming cans in 70 vacuum, the combination of a sealing chamber including a plurality of arcuate wall sections, means for adjusting said sections relative to each other and to the center of the chamber, means for securing the sections together, a continuously rotating can carrier in said chamber, means for vacuumizing cans in the can carrier, and means mounted in the can carrier for seaming caps onto cans there- 75 in.

5. In an apparatus for seaming cans in 80 vacuum, a rotatable can carrier, seaming devices within the can carrier, each of said seaming devices including a pair of seaming rollers, means within the carrier for moving the rollers of said pair of rollers toward each other, and means extending to the external portion of the can carrier for manually adjusting the pressure of the rollers of the pair 85 toward one another.

6. In an apparatus for seaming cans in 90 vacuum, a sealing chamber having an opening in its side for admission and discharge of cans and having an air passage in its inner surface at the bottom thereof, said passage 95 terminating short of the opposite sides of said opening, a port leading through the side of the chamber downwardly and outwardly from said passage, a suction tank in direct communication with said port, and a rotary can- 100 carrier within the sealing chamber adapted to close the opening in the side of the chamber and be closed by the wall of the chamber.

7. In apparatus for seaming cans in 105 vacuum, the combination of a sealing and vacuumizing chamber, means within said chamber for seaming caps onto cans, means for feeding cans and caps into the sealing and vacuumizing chamber, and means controlled by the passage of the cans for placing the caps 110 loosely on the cans as they pass into said chamber.

8. In apparatus for seaming cans in 115 vacuum, the combination of a sealing chamber having an air exhaust passage extending around a portion of its inner circumference, a continuously rotating can-carrier in said chamber, means for feeding cans and caps to the carrier, seaming devices mounted in the carrier, means for holding the cans and caps 120 against rotation until they reach a predetermined point in the length of the air exhaust passage, and means for then spinning the cans in contact with the seaming devices.

9. In apparatus for seaming cans in 125 vacuum, the combination of a sealing chamber having an air exhaust passage extending around a portion of its inner circumference, a continuously rotating can-carrier in said chamber, means for feeding cans and caps 130

- to the carrier, seaming devices mounted in the carrier, means for holding the cans and caps against rotation until they reach a predetermined point in the length of the air exhaust passage, means for then spinning the cans in contact with the seaming devices, means for arresting the spinning of the cans at a point beyond the air exhaust passage, and means for discharging the cans.
10. In means for seaming cans in vacuum, the combination of a sealing chamber, a continuously rotating can-carrier in said chamber, means for creating a vacuum in the chamber, means for feeding cans and caps into the carrier, levers fulcrumed in the carrier, seaming rollers on said levers, means between the rollers for holding the cans and caps initially against rotation and out of engagement with the seaming rollers, means whereby at a predetermined point in the travel of the carrier the cans and caps will be disposed in the plane of the seaming rollers and receive spinning motion, yieldable means acting on the levers to hold the seaming rollers away from the cans, and cams between the inner ends of the levers acting thereon to cause the rollers to successively engage the spinning cans.
11. In means for seaming cans in vacuum, the combination of a sealing chamber, a continuously rotating can carrier in said chamber, means for feeding cans and caps to said can carrier, means within the can carrier to support the cans and caps for travel with the can carrier, levers within the can carrier at opposite sides of the last-mentioned means, seaming rollers carried by said levers to engage the cans and caps, eccentric fulcrum pins supporting the levers, means for turning said pins to regulate the pressure of the rollers on a can, and means for rocking the levers to cause the rollers to successively engage the cans.
12. The combination of a sealing chamber, a transfer turret to deliver cans and caps to the sealing chamber, and means for feeding cans and caps to the turret, the turret including plungers receiving the caps and operable to place the caps loosely on the cans whereby the caps will be withdrawn by the cans as the cans pass to the sealing chamber.
13. The combination of a sealing chamber, a turret for delivering cans and caps to the sealing chamber, means for feeding cans to the turret, and means at one side of the turret for feeding caps to the turret, the last-mentioned means being controlled by the passage of the cans.
14. The combination of a sealing chamber, a turret for delivering cans and caps to said chamber, means for feeding cans to the turret, and means for feeding caps to the turret including a continuously operating slide, a cap-ejecting plunger, and means controlled by the passing cans to lock the plunger to the slide.
15. The combination of a sealing chamber, a turret for delivering cans and caps to said chamber, means for feeding cans to the turret and alining and spacing the cans, and means controlled by the passing cans for feeding caps to the turret.
16. The combination of a sealing chamber, a turret for delivering cans and caps to said chamber, a magazine for caps at one side of the turret, a continuously operating slide below and at one side of the magazine, a plunger for ejecting the lowermost cap from the magazine, means controlled by the passing cans to lock the plunger to the slide, and a laterally operating pusher to deliver the ejected cap to the turret.
17. The combination of a stationary casing, a continuously rotating can carrier for receiving assembled caps and cans and carrying them through the casing, said casing and carrier forming a vacuum chamber, means for subjecting the cans to a vacuum in the vacuum chamber, yieldable means within the can carrier for maintaining the caps in loosely assembled relation to the cans during the action of the vacuum, and means within the can carrier for subsequently clinching the caps on the cans.
18. In an apparatus for sealing cans in vacuum, the combination of a continuously rotating can carrier, a plunger mounted in the bottom of the can carrier to support a can, means for feeding loosely assembled cans and caps into the can carrier over the plunger, means for vacuumizing the cans, means for seaming the cans, a continuously rotating chuck in the top of the can, a non-rotating presser rod bearing on the cap during the vacuumizing period, and means whereby at the end of the vacuumizing period the rod will be withdrawn and the chuck will be caused to bear upon the cap and spin the cap and can in engagement with the seaming means.
19. In apparatus for sealing cans in vacuum, a rotating can carrier, means within the carrier for maintaining a can and cap in assembled relation, levers fulcrumed between their ends within the can carrier and arranged at opposite sides of the can therein, seaming rollers mounted at the outer ends of said levers, means between the inner ends of the levers for rocking them to cause the seaming rollers to alternately engage the cap and the can thereon, and means for spinning the can and cap in contact with the seaming rollers.
- In testimony whereof, I have signed this specification.
- ADOLPH K. MALMQUIST.
